To all whom it may concern:

Be it known that I, Hugh W. Vogl, a citizen of the United States, and residing in the village of Wilmette, county of Cook, and State of Illinois, have invented a new, original, and ornamental Design for a Vise or Similar Article, of which the following is the specification, reference being had to the accompanying drawings, forming a part thereof.

On the drawings:

Fig. 1 is a perspective view of a vise or similar article, showing my new design;

Fig. 2 is a front elevational view;

Fig. 3 is a rear elevational view;

Fig. 4 is a side elevational view; and

Fig. 5 is a top plan view.

I claim:

The ornamental design for a vise or similar article, substantially as shown.

HUGH W. VOGL.
